UNITED STATES PATENT OFFICE.

ELMER S. STACK, OF WEST SOMERVILLE, MASSACHUSETTS.

WATER CONNECTION.

1,109,946.

Specification of Letters Patent.

Patented Sept. 8, 1914.

Continuation of application Serial No. 722,432, filed September 26, 1912. This application filed July 31, 1913. Serial No. 782,387.

To all whom it may concern:

Be it known that I, ELMER S. STACK, a citizen of the United States, and resident of West Somerville, in the county of Middlesex and State of Massachusetts, have invented certain new and useful Improvements in Water Connections, of which the following is a specification.

The present invention relates to a connection designed and adapted to be used with a water tank and a water-heater for making communication between the delivery pipe which runs from the tank and the delivery pipe from the heater.

15 It is the object of the invention to enable hot water to be drawn from a hot water faucet or tap in the plumbing system with which the tank is connected when the heater is active, and the water in the tank is cold; 20 without mingling the cold water in the tank with the hot water coming from the heater; to enable hot water to be furnished for immediate use and delivered directly through the heater and piping, without first entering the tank, and within a brief time after 25 generating heat in the heater, when the body of water in the tank is cold; and to get hot water when there is any in the top of the tank and the heater is inoperative, without 30 permitting the colder water from the bottom of the tank to flow through the heater.

The present application is a continuation of my pending application for water connection filed September 26, 1912, Serial No. 35 722,432.

The manner in which my object is carried into effect is explained in the following specification in connection with the drawings forming a part of this application.

40 In the drawings, Figure 1 represents an elevation of a water tank and of a heater communicating with said tank and having its outlet joined to the outlet of the tank by my improved connection. Fig. 2 is an elevation of the upper part of the tank showing the coupling or connection applied to a different arrangement of delivery pipe. Figs 3 and 4 are views similar to Figs. 1 and 2 respectively showing a modified form of coupling or connection adapted to serve the same purpose and applied in the same way as that shown in Figs. 1 and 2. Fig. 5 is a detailed longitudinal section of the form of coupling shown in Figs. 1 and 2. Fig. 6 is a detailed

section of the coupling shown in Figs. 3 55 and 4.

The same reference characters indicate the same parts in all the figures.

In the drawings *a* represents a tank for containing hot water, *b* a pedestal or base 60 on which the tank is supported, *c* the inlet pipe for admitting cold water to the tank and *d* the delivery pipe for conducting hot water to hot water faucets of the plumbing system with which this apparatus is connected. 65

A heater *e* is shown in connection with the tank and is preferably although not necessarily a gas heater in which heat is developed by a gas flame. I prefer to use 70 in this connection such a heater as that illustrated in my pending application No. 700,441, which is especially designed to heat water instantaneously. This heater is connected with the lower part of the tank by 75 a pipe *f* and has an outlet pipe *g* leading outwardly from its upper end, which is connected with the discharge pipe *d* from the tank by a coupling or connection *h*. Said coupling *h* is in external form a *T* coupling 80 having threaded end connections *h'* and *h''* and a side connection *h'''*.

In the embodiment of the coupling shown in Figs. 1, 2, and 5 there is an internal elbow or angular conduit *i* which communicates with the side opening *h'''* and has its inner end directed toward the opening *h'* which is the end nearest the tank when the coupling is properly connected in place. The sides or walls of the elbow *i* are separated on all sides from the outer walls of the coupling, and the lip surrounding the orifice *i'* of the elbow is separated from the end of the coupling by a distance sufficient to permit water entering the coupling at 95 the end *h'* to pass through the coupling around the elbow to the opening *h''*. In the top of the elbow there is a vent *j* provided to prevent trapping of air or steam and thus causing an air lock which would interfere with the thermal circulation through the heater. 100

A modified form of coupling shown in Figs. 3, 4, and 6 has an outer shell substantially like that of the form already described with the end openings *h'* and *h''* and the side opening *h'''*. In the interior of this form of coupling there is a straight

tube k which is fastened at the upper end of the T in such a manner that water cannot pass by it at this end, and extends toward the opposite end k' and past the side opening k^2 . This inner tube is separated on all sides from the outer shell of the T and terminates sufficiently far short of the opening k' to permit flow past it between the openings k^3 and k' . A vent l is provided in the inner tube k to prevent formation of an air lock in the upper part of the surrounding space inclosed in the shell of the T .

In connecting the T in the pipe system, the upper or outer end of the T is connected with the hot water supply pipe d and the lower end, that is, the end k' is joined to the tank by a pipe d' , the coupling being entirely outside of the tank. The pipe g from the heater is connected with the side opening k^3 of the T . The coupling may be mounted in a rising supply pipe as shown in Fig. 1, or in a horizontally running pipe d^2 as shown in Fig. 2. The form of coupling shown in Fig. 6 is similarly connected in a rising or horizontally running hot water supply pipe as shown respectively in Figs. 3 and 4. In either case and with either form of coupling the coupling is so placed that the inner tube, by which term I include both the nozzle i of Fig. 5 and the tube k of Fig. 6, is directed toward the tank, and has that end which is surrounded by an annular space nearer to the tank than the opposite end.

In each form of coupling communication is provided between the end openings k' and k^2 and also from the side opening k^3 to each of the end openings, but the communication from the side opening to the upper end k^2 is interrupted by the inner tube so that water can not pass from the side opening to the upper opening except after being deflected from the shortest and easiest course. It is to be noted, however, that the water is not compelled to pass out of the T before it can flow from opening k^3 to the opening k^2 , and that therefore it is able to pass from the heater to the delivery pipe d without first entering the tank.

The employment of my improved coupling or T in combination with a tank and a heater enables hot water to be delivered to the faucet or tap whenever there is any hot water in either the tank or the heater, before any cold water will be delivered through the hot water pipe d . It also enables hot water to be delivered in a very brief space of time and with the least possible consumption of fuel when the water in the tank is cold. To explain these statements let it be assumed, first, that the water in the tank is cold and the heater is cold and that it is desired to obtain hot water at a faucet. The flame or fire in the heater

is then first kindled or turned up. Turning on the flame in the case of a gas heater may be accomplished conveniently and easily by the employment of a distant control such as is described in my application for patent, Serial No. 771,665, filed June 4, 1913, manipulated at the place where delivery of the water is desired. The device herein illustrated and the heater and control referred to together provide an efficient and economical system which is particularly convenient when small quantities of hot water are required on short notice, for furnishing the hot water immediately without waste of fuel and without effort on the part of the user. As soon as the heater becomes warm the column of water therein and in the pipe g becomes less dense, and therefore less heavy, than the parallel column in the tank and the pipe connection d' , and flows upwardly, discharging from the elbow i , and correspondingly passing around the end of the tube k , cold water flowing from the bottom of the heater through the pipe f , to take the place of the water which thus leaves the heater. As soon as the action begins the tap may be opened and the heated water then is delivered at the tap as soon as the cold water in the pipe d is displaced. As long as the tap remains open to an extent not exceeding the rate at which thermal circulation carries the water through the heater, only the hot water passing through the heater will be delivered at the tap and none of the cold water in the tank will be delivered, thus accomplishing the object of supplying the demand, which is frequent in domestic use, for small quantities of hot water in a short time without heating the water in the tank. This result is obtained because, first, the column of water in the heater and pipe g becomes, upon heating, lighter than the corresponding column in the tank and pipe d' , so that a circulation of water occurs with upward flow from the heater and downward flow through the tank and from the tank into the heater, which opposes direct flow from the tank through the pipe d' , and second, because the discharge of the hot water from the heater into the delivery pipe takes place in the chamber formed by the T , which is outside of the tank, so that there is no mingling of the heated water with the cold water in the tank.

When there is a body of hot water in the tank and the heater is inactive, that is, when the flame or fire is extinguished, opening of the hot water faucet allows the hot water, which collects at the top of the tank by reason of its specific gravity, to flow directly to the tap under the pressure of the water entering the tank through the inlet e , and there is no flow or by-passing of cold water from the bottom of the tank through the

heater, because the cold water from the heater can not pass to the pipe *d* except after flowing toward the tank in order either to escape from the elbow *i* or to enter 5 the inner tube *k*, and movement in this manner of water from the heater is resisted and prevented by the force of the current flowing from the tank through the *T*. The pressure acting upon the tank tends equally to 10 force the water through the pipe connection *d'* and through the heater, but the passage through the pipe *d'* and *T* is more direct than that from the heater through the elbow *i* or to the inner tube *k*, so that 15 upon opening the tap the flow starts first through the connection *d'* and chokes any flow from the heater due to pressure. When the heater is active and no water is withdrawn at any tap, a thermal gravity circulation 20 takes place between the heater and tank in the well known manner until all the water in the tank is heated to the capacity of the heater.

The tank may be connected to any other 25 heater than that shown, as for instance with a kitchen range or a furnace, and in such case the action would be the same as that described, the coupling causing the water to pass through the heater when the same 30 is active and causing the water to flow directly from the tank and not through the heater when the tap is opened and the heater is inactive.

It will be understood from the foregoing 35 description that my invention insures the delivery of hot water when any hot water is available, and that particularly it enables hot water to be furnished with a minimum expenditure of heat when the entire apparatus is cold.

It may be considered that the elbow *i* and tube *k* are two forms of baffle, each of which 40 interrupts the direct flow from the heater to the tank delivery pipe *d* and away from the tank and deflects the water toward the 45 tank before permitting it to pass from the heater away through the pipe *d*, but without compelling such water first to pass into the tank. It may also be considered that the 50 passage through the elbow *i* and the annular space around such elbow together form, in one embodiment of my *T*, a passage from the heater to the delivery pipe *d*, which is offset toward the tank and communicates 55 with the tank, and that the bore of the inner tube *k* and the annular space around such tube, provide an equivalent offset passage in the other illustrated embodiment of the invention, the passage in each instance being 60 contained wholly within the coupling and therefore permitting the water to flow through it without entering the tank.

Other forms and arrangements of baffles or partitions may be used, and all such 65 forms are within the scope of my invention

as provide a means for causing the flow of water from the tank to obstruct the flow from the heater when the latter is inactive, without compelling the hot water flowing from the active heater to enter the tank before passing away from the tank through the delivery pipe.

What I claim and desire to secure by Letters Patent is:

1. The combination of a tank, a heater, 75 means for conducting water to the tank, a connection between the lower part of the tank and the heater, a delivery pipe leading from the tank, and a coupling in said pipe having a lateral branch connected to the 80 heater, said coupling having internal means so constructed and arranged as to obstruct direct passage of water from said branch to said delivery pipe, and to permit the water issuing from said branch to enter said pipe 85 without passing into the tank.

2. The combination of a tank, a heater, means for conducting water to the tank, a connection between the lower part of the tank and the heater, a delivery pipe leading 90 from the tank, and a coupling in said pipe having a lateral branch connected to the heater, said coupling having a passage from said lateral branch to said delivery pipe, having means for deflecting toward the tank 95 the water issuing from the branch in its flow to the delivery pipe, and having a passage in its interior around the end of said deflecting means.

3. The combination of a tank, a heater 100 having an inlet connected with the lower part of the tank, a delivery pipe leading from the tank, a pipe leading from the heater, and a coupling connecting said pipes, having a passage arranged to permit flow of 105 water from the heater to the delivery pipe and away from the tank without first entering the tank, and having means for deflecting the flow from the heater toward the tank.

4. The combination of a tank, a heater having an inlet connected with the lower part of the tank, a delivery pipe leading from the tank, a pipe leading from the heater, and a coupling connecting said pipes, 115 said coupling having an internal passage between the respective pipes offset toward the tank, but entirely outside of the tank, and the delivery pipe having an intervening passage between said offset passage and the 120 tank.

5. The combination of a tank, a heater having an inlet connected with the lower part of the tank, a delivery pipe leading from the tank, a pipe leading from the 125 heater, and a coupling connecting said pipes, said coupling being provided with a baffle between its inlet from the heater and its outlet to the delivery pipe so arranged as to cause water flowing from 130

the tank to oppose flow from the heater, and at the same time to provide a passage within the coupling from the heater to the outwardly running delivery pipe.

5 6. The combination of a tank, a heater having an inlet connected with the lower part of the tank, a delivery pipe, a pipe leading from the heater, and a coupling connecting said pipes, said coupling having an 10 end opening communicating with the tank, an opposite end opening connected with the delivery pipe, and a side opening connected with the pipe from the heater, and having also an internal baffle located wholly between the said end openings and arranged 15 to deflect water entering said side opening toward the first end opening before passing to the second end opening.

7. The combination of a tank, a heater 20 having an inlet connected with the lower part of the tank, a delivery pipe, a pipe leading from the heater and a coupling for said pipes, said coupling having an end opening communicating with the tank, a side opening 25 connected with the pipe which leads from the heater, an opposite end opening connected with the delivery pipe, and a baffle comprising a conduit leading from the side opening and toward the first end 30 opening, but terminating within the cou-

pling, said conduit being open at both ends, and the coupling having an internal space surrounding the conduit and crossing one end thereof and in communication with the end openings.

8. The combination of a tank, a heater, an inlet connection to the heater from the bottom of the tank, an outlet pipe from the heater, an outlet pipe leading from the tank, and a T connection in said outlet pipe having an opening in its side coupled with the pipe leading from the heater and having an elbow or nozzle in its interior extending from said side opening and directed toward the tank.

9. The combination with a water tank of an outlet pipe, a T coupling in said outlet pipe having an opening in one side and having an internal elbow extending from said opening and directed toward the tank, and 40 a heater connected, respectively, with the bottom of the tank and with the side opening in said coupling.

In testimony whereof I have affixed my signature, in presence of two witnesses.

ELMER S. STACK.
